UNITED STATES PATENT OFFICE.

HARRY NAGIN, OF BROOKLYN, NEW YORK, ASSIGNOR TO THE GRATING COMPANY OF AMERICA, OF PITTSBURGH, PENNSYLVANIA, A CORPORATION OF PENNSYLVANIA.

CONNECTED BAR STRUCTURE.

Application filed January 28, 1926. Serial No. 84,311.

My invention relates to a new and improved connected bar structure.

One of the objects of my invention is to provide a structure consisting of a series of 5 longitudinal bars and a series of cross-bars in which the cross-bars are immovably connected to the longitudinal bars in a simple, reliable and efficient manner, so that the cross-bars are positively locked against 10 movement with respect to said longitudinal bars, in any direction.

Another object of my invention consists in making a connected bar structure of this 15 type which is useful for gratings in side-walks or at other points, for protecting windows and for other purposes, in which the cross-bars are very firmly and reliably connected to the longitudinal bars without the necessity of using rivets.

20 Other objects of my invention will be set forth in the following description and drawings which illustrate a preferred embodiment of my invention, it being understood that the above statement is intended merely to generally explain the same and not to limit it in any manner.

Fig. 1 is a top view.

Fig. 2 is a section on the line 2—2 of 25 Fig. 1.

Fig. 3 is a section on the line 3—3 of Fig. 2.

The structure consists of a series of bars 10 which may be called longitudinal bars, and a series of cross-bars 11. The longitudinal bars 10 are provided with recesses 13, each said recess consisting of two or more relatively inclined portions. In the particular embodiment illustrated herein, each recess 13 has two relatively inclined portions, namely a main or body portion which is substantially perpendicular to the edge of the respective bar 10, and an inner inclined locking branch.

Each longitudinal bar 10 may have the 45 inclined inner locking branches of the recesses 13 inclined in the same direction. However, each row of recesses in the consecutive bars 10, along a line perpendicular to the respective bars 10, preferably has the 50 respective locking branches thereof inclined in opposite directions. This is illustrated in Fig. 2, because if it is assumed that the front bar 10 has the locking branches of its recesses inclined towards the right, then the 55 next or the second bar 10 has said locking

branches inclined towards the left, etc. The cross-bars 11 are preferably unslotted.

After the structure is loosely assembled, the cross-bars 11 are subjected to very high pressure, as by means of a hydraulic press or 60 the like, so that the bottoms thereof are forced into the inclined branches of the recesses 13. This causes the bottoms of the cross-bars 11 to be bent laterally so as to form lateral portions 12 which fit within the 65 inclined locking branches of the recesses 13. I prefer to have the recesses 13 of the same width throughout, and it is not necessary to thicken or enlarge the bottoms of the cross-bars 11 in order to secure a very firm grip 70 between the cross-bars and the longitudinal bars. Since the laterally bent portions 12 of the cross-bars 11 are alternately inclined in opposite directions, a very firm hold is secured.

75 In order to positively lock the cross-bars 11 from any movement in a direction parallel thereto, I prefer to have each cross-bar 11 of a height or width which is slightly greater than the length of the corresponding recess 13.

80 Hence, when sufficient pressure is applied to force the cross-bars 11 into position, this forces the material at the bottoms of the cross-bars 11 to spread beyond the bottoms 85 of the locking branches of the recesses 13, so that short tongues 14 are thus produced. These tongues 14 are shown on a very much exaggerated scale in Fig. 3. Each cross-bar 11 is therefore provided with two longitudinal locking tongues 14 which positively 90 engage the respective longitudinal bar 10.

95 Hence, the strength of the grip between the various bars does not depend only on a frictional grip, but a positive interlocking is secured.

This method of manufacture differs from that in which the cross-bars are initially formed with recesses in the bottom thereof, so that the walls of said recesses can form 100 tongues which grip the longitudinal bars. On the contrary, according to the present invention, the material at the bottoms of the cross-bars is caused to flow or become distorted under the action of the very high pressure utilized, so that the lateral locking tongues 14 are produced either wholly or in part as the result of said high pressure, and hence these lateral locking tongues 105 frictionally grip the longitudinal bars adja- 110

cent the bottoms of the recesses 13. The longitudinal bars and the cross-bars are made of any suitable metal.

It would not be departing from my invention if the outer body portions of the slots or recesses 13 would not be perpendicular to the longitudinal edges of the longitudinal bars. The inclined locking branches of the slots 13 could have any desired shape or curvature and could be composed of several portions relatively inclined to each other. Of course, as a matter of manufacturing convenience it is desirable to use ordinary flat strips of rolled material and to force these into a crooked slot. In the illustrated form of the invention, the slot is crooked at the bottom thereof, it consisting of an upper straight portion and a bottom curved portion.

20 I have shown a preferred embodiment of my invention, but it is clear that numerous changes and omissions could be made without departing from its spirit.

I claim:—

25 1. A connected bar structure comprising a plurality of girder bars having slots formed in a side thereof, and cross bars lying in the slots, a slot in one girder bar being of a different cross sectional shape than a slot in 30 an adjacent girder bar which is engaged by

the same cross bar, the portions of the cross bar which are engaged by the slots being permanently deformed to fit the slots.

2. A connected bar structure comprising a plurality of girder bars having crooked 35 slots formed in the longitudinal edges thereof, the slots being of substantially constant width from top to bottom, and being of different cross sectional shape in different girder bars as viewed from the same 40 side, and a cross bar having portions fitting into the slots, the portions of the cross bar intermediate the slots being generally flat and the portions engaged by the slots being crooked to hold the cross bar in place. 45

3. A connected bar structure comprising a plurality of girder bars each having slots therein of substantially constant width from top to bottom, the slots at their upper portions being substantially straight and being 50 curved at their lower portions, the lower portions of the slots in different cross bars being inclined in different directions, and a cross bar fitting into the slots, the portions of the cross bar which are engaged by the 55 slots being deformed to correspond with the slots and hold the cross bar in place.

In testimony whereof I affix my signature.

HARRY NAGIN.
